UNITED STATES PATENT OFFICE.

EVELYN MAY WEATHERBEE, OF NEW YORK, N. Y.

MANICURIST'S BUFFER.

No. 908,917.

Specification of Letters Patent.

Patented Jan. 5, 1909.

Application filed January 20, 1908. Serial No. 411,614.

To all whom it may concern:

Be it known that I, EVELYN MAY WEATHERBEE, a subject of the King of Great Britain, and a resident of the city of 5 New York, in the county of New York and State of New York, United States of America, have invented certain new and useful Improvements in Manicurists' Buffers, of which the following is a specification.

10 My invention relates to manicurists' buffers and its object is to improve upon devices of this kind and to provide a simple arrangement of parts by means of which the usefulness of the article is increased.

15 I will describe my invention in the following specification and point out the novel features thereof in claims.

Referring to the drawings, Figure 1 is a side elevation of a manicurists' buffer made 20 according to my invention. Fig. 2 is a plan view of the same article with one of its parts broken away to more clearly show its construction. Fig. 3 is a sectional end elevation of my improved buffer, the section being 25 taken on the line 3—3 of Fig. 2. Fig. 4 is a sectional elevation, on an enlarged scale, of some of the parts of this device, the section being taken on the line 4—4 of Fig. 2. This view shows a detail of construction. In Fig. 30 5 a modification of my invention is illustrated. This is a plan view of a buffer of novel construction with its cover-plate removed. Fig. 6 is a sectional view taken on the line 6—6 of Fig. 5, showing on an enlarged scale a detail of construction.

Like characters of reference designate corresponding parts in all of the figures and the specification.

10 is a block of wood or other suitable material which forms the body portion of the buffer. The upper edge of this block is rabbed to form a groove or kerf 11.

12 designates a padding which is preferably built up of a number of layers of felt or 45 similar material in the usual manner.

13 is a cover-plate preferably of wood, the shape of which conforms in plan view with the shape of the top of the block 10. In side elevation this cover-plate may have slightly 50 more curvature than has the top of the block 10 so that when it is placed loosely upon the latter its ends only will touch.

14 is a cover of soft leather such as chamois or other desired material.

55 All of the above parts are well known in the art and need no further description here.

20 designates a knob or handle to which is attached a screw 21.

22 is a metallic bushing inserted in the central portion of the block 10 and threaded to 60 receive the screw 21. A hole through the center of cover-plate allows this screw to pass freely through it.

23 is a separate or loose metallic rim which conforms to the shape of the block 10 and fits around the rabbeted edge 11. The cross-sectional shape of this rim is shown in Fig. 4 from which it may be seen that it has a comparatively flat body with a downwardly projecting flange on its outer edge. 70

In using this buffer a piece of chamois skin is placed over the padding and the block after which the metallic clamping rim 23 is put in position. The chamois may then be readily drawn in under the rim until it is 75 properly stretched over the body of the buffer. After this the edges of the chamois may be trimmed off with a knife or a pair of shears and the cover-plate 13 placed over the whole. The handle 20 is then screwed into the body 80 portion until the cover-plate is firmly clamped down onto the rim 23. This simple operation is all that is necessary to affix the chamois to the buffer, and it may be repeated and the chamois cleansed and replaced or a 85 new chamois affixed as often as desired. Thus the renewal of the chamois which is so difficult and laborious in other structures of this nature is facilitated and made a very simple matter. Moreover, when in use, the 90 rim 23 adds materially to the appearance of the finished article.

In the modification shown in Figs. 5 and 6 the metallic rim is made in two parts 15 and 16 which are pivoted together and to the 95 block 10 at 17. In placing a chamois upon the buffer in this case these two parts are spread apart into the position in which one of them is shown in dotted lines at 16^a, and after the leather has been placed in position, they 100 are drawn together and fastened by a screw 18. The lower edge of the metallic pieces forming the rim is brought down to a sharp edge as at 19 which points inwardly and which engages with the chamois and tightens 105 it over the body of the buffer as these parts are brought together. The cover-plate may then be screwed to the buffer in the manner previously described.

Buffers of this kind are often rendered use- 110 less by the leather covering becoming soiled. They are often made with costly ornamental

tops and therefore it is desirable that the soiled part be renewed. In attempting to replace the chamois by tucking its edges into a slit or groove according to the former 5 method these tops easily become mutilated and ruined. As these are often made of the precious metals or of costly woods this is a serious difficulty, but is one which is entirely overcome by the present invention.

10 I have illustrated more than one form of my invention to show that I do not limit myself to any specific form of construction. I have mentioned chamois skin as the outside cover as this is the material usually employed. But other flexible material may be used such as paper. I sometimes use several 15 layers of paper so that by tearing off one layer at a time a fresh surface is at once available. This is a valuable feature for 20 sanitary reasons especially when the buffer is used in public manicure parlors as a new clean surface may then be used for each individual.

What I claim is.—

- 25 1. In a manicurists' buffer, the combination of a body portion, a flexible covering therefor, a cover-plate, and a separate clamping member between the body portion and the cover-plate arranged to hold said covering onto the body portion.
- 30 2. In a manicurists' buffer, the combination of a body portion, a flexible covering therefor, a cover-plate, a separate clamping member, and means for pressing said separate member against a portion of the covering to clamp said covering onto the body portion of the buffer.
- 35 3. In a manicurists' buffer, the combination of a body portion, a leather covering

therefor, a cover-plate, a separate clamping 40 rim between the body portion and the cover-plate and fitting around the upper edge of the body portion, and means for clamping all of said parts together.

4. In a manicurists' buffer, the combination 45 of a body portion, a leather covering therefor, a cover-plate, a separate clamping rim between the body portion and the cover-plate, and a handle with a screw affixed thereto arranged to take into the body portion and to clamp all of said parts together. 50

5. In a manicurists' buffer, the combination 55 of a body portion, the upper edge of which is cut away to form a kerf, a leather covering for said body portion, a clamping rim having a depending flange, a cover-plate engaging with said rim, and a handle with a screw affixed thereto arranged to take into the body portion and to clamp all of said parts together. 60

6. In a manicurists' buffer, the combination 65 of a body portion, the upper edge of which is cut away to form a kerf, an internally threaded bushing in the body portion, a flexible leather covering for said body portion, a clamping rim having a depending flange, a cover-plate engaging with said rim, and a handle with a screw affixed thereto arranged to take into the threaded bushing and to clamp all of said parts together. 70

In testimony whereof I have signed my name to this specification in the presence of two subscribing witnesses.

EVELYN MAY WEATHERBEE.
